UNITED STATES PATENT OFFICE

2,056,231

RAILWAY CAR

William H. Mussey, Chicago, Ill., assignor to Pullman-Standard Car Manufacturing Company, Chicago, Ill., a corporation of Delaware

Application July 19, 1934, Serial No. 735,944

2 Claims. (Cl. 105—397)

This invention relates to railway cars and has for its principal object to reinforce the intersection of the car sides with the car floor by using seat supports as gussets, thereby obviating the necessity of employing other bracing which would unnecessarily add to the total weight of the car.

Further and other objects and advantages will become apparent as the disclosure proceeds and the description is read in conjunction with the accompanying drawing, in which

Fig. 1 is an illustrative, diagrammatic, perspective view of car body framework;

Fig. 2 is a fragmentary, cross sectional view showing the seat pedestals mounted in accordance with the teachings of this invention; and

Fig. 3 is a perspective view of the seat pedestal mounting.

But this specific illustration is for the purpose of disclosure only and the appended claims should be construed as broadly as the prior art will permit.

In the illustrative embodiment of the invention, the car framework consists of a center sill 10, end sills 11 and 12 secured to opposite ends of the center sill, door end posts 13, 14, 15 and 16 rising from the end sills, top anti-telescoping plates 17 and 18 which rest upon the door end posts, and top sills 19 and 20 supported by the end posts and connected at the top and bottom by plates 21 and 22 which, with the top sills, form a box girder extending from one end of the car to the other. All of these structural members are preferably made of aluminum alloy, and together constitute the main framework of the car.

The shell of the car is formed by a plurality of curved ribs 23 which extend from the top sills 19 and 20 to the upper portion of the center sill 10. The ribs lie in vertical planes and are connected together by various longitudinal framing members, such as a roof stringer 24, a window header stringer 25, a belt rail 26, a seat stringer 27, a seat sill 28, a side sill 29, and a plurality of floor stringers including an inverted channel 30.

The belly of the car is formed by arcuate bars 31 which extend from the side sills 29 to the bottom of the center sill 10. These bars are strengthened by struts 32 and 33.

A metal skin 34 is applied to the exterior of the skeleton framework, as shown in Fig. 2.

The intersections of the car sides with the car floor are reinforced by seat pedestals 35 which extend between the seat sills 28 and the stringer

30. The pedestals are Y-shaped and hollow and include a leg portion 36, and arms 37 and 38. The leg 36 is secured to the floor stringer 30 by fastener plates 39 and angle brackets 40, as shown in Fig. 3, and the arm 37 rests upon, and is secured by rivets, or equivalent means, to an inwardly extending flange 41 formed integrally with the seat sill 28. In this way, the seat pedestal serves as a gusset to reinforce the lower corner of the car body. 10

Cushioned seats 42, the particular form of which is unimportant here, are supported by the seat pedestals 35, as shown in Fig. 2.

The seat sill arrangement disclosed in this application has been claimed in the application 15 of Martin P. Blomberg, Ser. No. 735,361, filed July 16, 1934.

The invention may be variously embodied within the scope of the appended claims.

What I claim, therefore, is:—

1. In a railway car, skeleton framework including upwardly extending ribs, and a longitudinal side framing member secured to said ribs, the combination of a seat sill connected to said ribs and having an interlocking connection with said side framing member and provided with an inwardly extending flange, a floor sill extending longitudinally of the car, a pedestal seated on said sill and having inwardly and outwardly extending arms at its upper end, brackets for rigidly connecting said pedestal to said floor sill, said outwardly extending arm resting on and rigidly secured to said flange and forwardly facing cushioned seats supported by 20 said arms, whereby the pedestal serves as a gusset to strengthen the connection between the side and floor framing. 30

2. In a railway car having a framework provided with upstanding ribs, a side frame member 40 rigidly connected to said ribs, a floor sill extending longitudinally of said car, a one-piece Y-shaped pedestal seated on said sill and extending upwardly therefrom, means for rigidly connecting said pedestal to said sill, one of the arms 45 of said pedestal extending outwardly and rigidly connected to said side frame member whereby the pedestal serves as a gusset to strengthen the connection between the side and floor framing, and the other arm of said pedestal extending inwardly therefrom, and cushioned seats fac-

ing forwardly mounted on and supported by said arms. 50
